UNITED STATES PATENT OFFICE.

NORRIS ELMORE CLARK, OF PLAINVILLE, CONNECTICUT.

RETICULATED METAL FABRIC.

1,113,195.

Specification of Letters Patent.

Patented Oct. 13, 1914.

Application filed July 1, 1908. Serial No. 441,822.

To all whom it may concern:

Be it known that I, NORRIS ELMORE CLARK, a citizen of the United States, residing at Plainville, in the county of Hartford and State of Connecticut, have invented certain new and useful Improvements in Reticulated Metal Fabrics, of which the following is a specification.

This invention relates particularly to lathing, roofing, sheathing and similar structures for affording support or reinforcement to walls, roofs, floors, ceiling, etc., where cement, plaster or concrete is used.

The main object is to provide a light but strong fabric which can be made and erected cheaply and which will receive the plastic material properly and hold it securely. The proportions and design may be varied considerably to suit different conditions of use. The form shown is adapted to be used without any centering. In its preferred form it consists of longitudinal members having lateral extensions connected by bridges whose upper members are connected. The terms upper and lower, longitudinal and transverse are relative and not intended to limit the fabric to use in a horizontal, vertical or inclined position.

Figure 1, is an end view of a fragment of fabric embodying my invention. Fig. 2, is a plan view of part of the same. Fig. 3, is a section of the fabric on the plane of the line X—X Fig. 2. Fig. 4, is a perspective view of a fragment of fabric. Fig. 5, is an end view of fabric, the longitudinal members of which are corrugated or folded.

For convenience in reference the main longitudinal members 1, 2 and 3 will be termed rods. Their cross-sectional shape is immaterial. Extending laterally from the side rod 1, are a series of cross bars such as 4 and 5. Similar cross bars such as 6, 7, 8 and 9 project from the rods such as 2.

The pairs of strands 10, 11 and 12, 13 form arches which support the beam 14. The beams 14, 15, etc., are preferably connected by a longitudinal rod 16. The arches between the rods are inclined away from each other, the interior angle γ being preferably somewhat less than 90° . The inclined arches and the beams form rigid bridge-like trusses which will support great weights. The ends of the strands preferably project downward so as to form feet 17 and 18 on which the

fabric can rest and be raised a little from the form or centering when it is used.

The fabric is integral and may be formed by cutting or slitting a sheet of metal and then bending the strands in the manner shown by any suitable mechanism. As illustrated in Figs. 1, 2, 3 and 4 the sheet has been stretched or expanded laterally so as to form openings 19, 20, etc. The size of these openings will depend upon the proportions of the members and the degree of lateral expansion.

Where greater strength is desired, the rods 21, 22 may be made wider and folded or corrugated as shown in Fig. 5. This increases the stiffness and the lateral folding or bending of the rods brings the inclined members 23, 24 and 25 nearer together thus diminishing the size of the openings. There is no need for any centering when this type of fabric is used for cement, concrete or plaster reinforcement. The corrugation may be sufficient to compensate for or negative the lateral expansion incident to the bending of the strands. In this case the product is of the same or less area than the original sheet.

The fabric illustrated is the same on both sides so that it is reversible. This is also more uniform in strength than it would be if for instance the upper rod 16 were omitted from the structure of Fig. 4. The spaces 26 and 27 between the inclined members are undercut or dove-tailed in section so that when the fabric is embedded in cement or the like, the anchorage is very secure. Even in light weight metal the fabric is stiff enough to permit walking upon it when erecting a floor or roof.

What I claim is:

1. An integral openwork fabric comprising rods in one plane having laterally projecting bars, inclined arches projecting transversely therefrom and bars in another plane parallel to the plane of the first bars and connecting the upper ends of said arches, each arch consisting of two strands parallel to each other.

2. An expanded metal fabric comprising reticulated sections forming plaster receiving surfaces in one plane, reticulated sections forming plaster receiving surfaces in another plane spaced apart from but parallel to the first mentioned plane, the edges of the sections in one plane overlapping the

- edges of the adjacent sections in the other plane and inclined transverse strands connecting the adjacent overlapping edges of adjacent reticulated sections and forming 5 dove-tailed shaped spaces.
3. An integral reticulated fabric comprising parallel rods in one plane, bars in the same plane projecting perpendicularly from said rods, bars in another plane parallel to the first mentioned bars and transverse strands extending relatively at right angles to said rods and connecting the adjacent ends of bars in the two planes.
4. An integral openwork fabric comprising 15 two series of rods lying in different but parallel planes, a series of parallel bars projecting laterally from each rod and transverse strands connecting the ends of the bars of adjacent rods and inclined so as to form 20 dove-tailed shaped spaces between them.
5. An integral openwork fabric comprising a series of parallel rods, bars projecting laterally therefrom, parallel strands connected with said bars and extending at an 25 angle thereto and having downwardly projecting feet and cross bars connecting the upper ends of opposite strands in a plane spaced apart from the plane of said rods.
6. An integral openwork fabric comprising 30 two series of rods in parallel planes, a series of bars projecting laterally from each rod and forming in conjunction therewith two spaced plaster supporting surfaces, transverse parallel strands connecting the 35 ends of said bars and oppositely projecting feet at the points of connection.
7. An integral openwork fabric comprising a series of parallel rods, a series of bars projecting laterally therefrom, inclined 40 arches rising from adjacent bars and having their tops extending out of the plane of said rods and bars connecting the tops of the opposite arches in a plane spaced apart from the plane of said rods, each arch consisting of two parallel strands.
8. An integral openwork fabric comprising 45 two series of rods lying in different but parallel planes, a series of parallel bars projecting laterally from each rod and trans-
- verse strands connecting the ends of the bars 50 and inclined so as to form dove-tailed shaped spaces between them, some of said rods being corrugated.
9. An integral openwork fabric comprising a series of parallel corrugated rods, bars 55 projecting laterally therefrom, inclined transverse strands connected to said bars and extending at an angle thereto and having downwardly projecting feet and members connecting the upper ends of said 60 strands in a plane spaced apart from the plane of said rods.
10. An integral openwork fabric comprising sets of parallel bars arranged in parallel spaced planes, rods connecting the bars in 65 one plane, transverse arches connecting the bars in the two planes and spacing feet projecting from the arches beyond each plane, each arch consisting of two parallel strands.
11. A dovetail corrugated expanded metal 70 element comprising three parallel ribs, a central rib lying in the base of the corrugation in a plane parallel to that of the two outer ribs, said central rib being connected to the two outer ribs by zigzag bar members 75 forming the sides and portions of the base of said corrugation.
12. An expanded metal sheet having a series of longitudinally extending dovetail corrugations formed therein, the base of 80 each corrugation lying in a plane parallel to the general plane of the sheet, a rib formed in the center of the base of each corrugation, said rib being connected to parallel ribs in said sheet by zigzag bar members forming the sides and portions of the 85 base of said corrugation.
13. A dovetail corrugated reinforcing element composed of an expanded metal sheet having a longitudinal rib formed in the center of the base of each corrugation, said ribs being integrally connected by zigzag bar members forming the sides and portions of the bases of said dovetail corrugations.

NORRIS ELMORE CLARK.
